UNITED STATES PATENT OFFICE

2,502,047

WINDROW PICKUP MACHINE

John Johnson, Brockton, Mont.

Application October 29, 1948, Serial No. 57,263

6 Claims. (Cl. 56—362)

1

This invention relates to a windrow pick-up machine, and more particularly to an improved straw-walker bar and pick-up finger assembly for such a machine.

It is among the objects of the invention to provide an improved straw-walker bar or lifting bar and pick-up finger assembly for a windrow pick-up machine, which assembly includes a straw-walker bar having at its lower end a movable pick-up finger pivotally connected to the bar and spring biased to its normal operative position in which it constitutes an uninterrupted continuation of the bar, such pick-up finger being movable relative to the bar against the force of a spring when an obstruction, such as a large stone or stump, is encountered, to avoid damage to the assembly, and which walker-bar and pick-up finger assembly is of simple and durable construction, and includes a pick-up finger having an outer or distal end firmly engageable with the ground to gather up all of the material in a windrow without skipping, and which will pick up and convey small pieces of material and loose seed, as well as the larger pieces of material, such as hay or straw.

Other objects and advantages will become apparent from a consideration of the following description and the appended claims in conjunction with the accompanying drawing, wherein:

Figure 1 is a side elevation of a windrow pick-up machine including straw-walker bar and pick-up finger assemblies, illustrative of the invention, operatively mounted thereon, portions being broken away and shown in cross-section to better illustrate the construction thereof;

Figure 2 is a bottom plan view of a fragmentary portion of the assembly including the pick-up finger and the adjacent portion of the straw-walker bar;

Figure 3 is a side elevation of a straw-walker bar and pick-up finger assembly, a portion being broken away and shown in cross-section substantially in the plane of the section line 3—3 of Figure 2; and

Figure 4 is a side elevation of a fragmentary portion of the assembly illustrated in Figure 3, showing the operation of the pick-up finger when encountering an obstruction, such as a stone.

With continued reference to the drawing, the improved pick-up machine comprises, in general, a U-shaped main frame 10 supported at its front end on a pair of caster-wheel assemblies 11 and at its rear end by a pivoted hitch 12 adapted to be secured to the guard or sickle bar of an associated harvester-thresher combination, a pair of crankshafts 13 and 14 journaled on the main frame, an outer sub-frame 15 and an inner sub-frame 16 mounted on the crank pins of said crankshafts, a plurality of straw-walker bars 17 mounted on said sub-frames by suitable bracket

2

and link assemblies, pick-up fingers 18 extending downwardly and forwardly from the front ends of the straw-walker bars to engage the ground at the front end of the machine, and spring means 19 resiliently holding the pick-up fingers in ground-engaging position.

The main frame 10 is preferably a U-shaped, tubular structure having legs 20 inclined upwardly and forwardly near the front open end 10 of the frame and having at its rear end a transverse bight portion 21.

Each of the wheel assemblies comprises a bracket 22 secured to the front end of the corresponding frame leg 20 and having a substantially vertical, intermediate portion with apertured end portions 23 extending forwardly from the intermediate portion, a post 24 extending through and journaled in the apertures of the end portions 23 of the bracket with its upper end above the corresponding frame leg and its lower portion inclined downwardly and rearwardly to provide a wheel-carrying arm 25, the end of which is perpendicularly extended to provide an axle 26 for the corresponding caster wheel 27.

A bracket 28 is secured to the upper end of the post 24 and has an outwardly-extending apertured arm through which extends a threaded pin 29, the lower end of which is connected to

30 the upper end of a tension spring 30. The lower end of spring 30 is connected by a suitable eye 31 to the front end of the corresponding frame leg 20. Pin 29 is adjustably secured to the bracket 28 by a nut and lock-nut assembly 32, so that the tension on the spring can be varied to raise and lower the front end of the frame relative to the wheel 27. A cylindrical cam element 33 surrounds and rotatively receives the post 24 and has its upper end secured to the under-side of the upper-bracket portion 23, and its lower end diagonally cut to cooperate with the diagonally cut upper end of a similar cam element 34 secured on the post 24 between the bracket end portions 23. With this arrangement, when the machine is turned, the caster wheels will rotate the posts and the corresponding brackets 22, and the operatively associated cam elements 33 and 34 of each wheel assembly will raise the front end of the machine to lift the lower ends of the pick-up fingers from the ground, so that these fingers do not drag on the ground during the turning of the machine, and will not be bent or broken by lateral forces imposed thereon.

45 The hitch assembly 12 comprises a pivot plate 35 secured to the rear side of the bight 21 of the frame substantially at the mid-length location of the latter, and a flat hitch bar 36 extending along the rear side of the frame bight substantially parallel to the latter. This hitch bar is

50 55 60

pivotedly secured to the frame by pivot bolt 37 extending through the center of the pivot plate 35, and is provided near each end with a rearwardly-extending, apertured lug 38, which lug are attached by means of suitable brackets 39 to the guard or sickle bar 40 of the harvester-thresher combine. A pair of substantially vertical plates 41 is secured to the frame bight, one near each end thereof, and a respective C-clip 42 is secured to each plate 41 to overlie the corresponding end of the hitch bar 36 to hold the ends of the hitch bar to the main frame and minimize end strains in the hitch assembly during turning of the machine. The pivotal connection between the hitch bar and the main frame of the pick-up machine permits the combine and the windrow pick-up machine to tilt or rock relative to each other as the two machines pass together over rough or uneven ground, so that the attachment of the pick-up machine to the combine imposes no undue strain on either machine.

A cross-member 43 extends transversely across the frame 10 and is secured at its opposite ends to the legs 20 near the mid-length location of the latter to reinforce the frame and hold the front ends of the legs 20 against movement relative to each other. This cross-member is bent downwardly so that it extends across the frame below the level of the frame legs and does not interfere with the operation of the machine.

The two spaced-apart, substantially parallel crankshafts 13 and 14 are journaled near their opposite ends in pillow blocks 43 mounted on the main frame legs 20 intermediate the length of the latter, the two shafts being journaled, one near each end of each pillow block and secured in operative position on the pillow blocks by corresponding bearing caps 44 secured to the tops of the pillow blocks. Each of these crankshafts has at each end an arbor journaled in the corresponding, frame-carried pillow block, has an intermediate portion in axial alignment with the end arbors, and has between each end arbor and the adjacent end of the intermediate portion a pair of crank throws, the pins of which are rotationally spaced apart approximately 180 degrees, the axes of all of the pins being substantially in a common plane.

The outer sub-frame 15 is a rectangular structure having similar, parallel end-walls 51 in the form of vertically-disposed, rectangular plates extending transversely of the frame, and side-walls or members 50 in the form of angle irons secured at their opposite ends to the spaced-apart end-walls 51. This first or outer sub-frame is supported on the outer crank pins of the two crankshafts by a pair of pillow blocks attached one to the top of each of the side members 50, so that when the two crankshafts rotate in the proper direction the sub-frame will move forwardly, upwardly, rearwardly, and then downwardly.

The second, or inner sub-frame 16 is also a rectangular body having end-walls 54 in the form of vertically-disposed, rectangular plates extending transversely of the frame and in spaced-apart, substantially parallel relationship to each other, and side-members 53 in the form of spaced-apart, substantially parallel angle irons connected at their opposite ends to the two end-walls 54 near the lower edges of the latter. This inner sub-frame is journaled on the inner crank pins of the two crankshafts 13 and 14 by suitable pillow blocks 55 secured one on the upper surface

of each of the side-members 53. The inner or sub-frame 16 thus has a movement similar to the movement of the outer sub-frame 15 when the two crankshafts are rotated, but displaced 180 degrees from the rotational phase of the outer sub-frame. The inner sub-frame is shorter than the outer sub-frame by an amount sufficient to permit free clearance of the adjacent end-walls of the two sub-frames as the sub-frames are revolved about the axes of the two crankshafts.

A plurality of upstanding, forwardly-inclined brackets 56 are secured in substantially, uniformly, spaced-apart relationship to the rear end-wall of the outer sub-frame 15 and a plurality of similar, upstanding, rearwardly-inclined brackets 57 are secured to the front end-wall of this outer sub-frame. The brackets 56 and 57 are provided with apertures in their upper ends and respective links 58 are pivotally secured at their lower ends to the upper ends of brackets 56, while respective links 59 are pivotally secured at their lower ends to the upper ends of the brackets 57. The links 58 extend upwardly and are pivotally connected at their upper ends to alternative straw-walker bars 17. Each front link 59 has in its upper portion an elongated slot and a respective pivot pin extends through each corresponding walker bar and through the slot in each link 59 to pivotally connect the walker bars to the links. Each walker bar is supported by two links carried by the same sub-frame and aligned forwardly and rearwardly with each other. The rear links 58 are longer than the front links 59 so that the walker bars are inclined rearwardly and upwardly, as is particularly illustrated in Figure 1.

Spaced-apart, upstanding brackets 60 are secured to the rear end-wall 54 of the inner or second sub-frame 16 in uniformly, spaced-apart relationship, and rear links 61 are pivotally connected at their lower ends to the apertured upper ends of these rear brackets and at their upper ends to corresponding walker bars 17 interposed between the walker bars supported by the bracket-and-link assemblies carried by the outer sub-frame 15. Brackets 62 extend upwardly and forwardly from the front end-wall of the inner sub-frame 16, and front links 63 are pivotally connected at their lower ends to the apertured upper ends of respective brackets 62. Each front link 63 is provided near its upper end with an elongated, longitudinally-extending slot 64, and a respective pivot pin 65 extends through the corresponding walker bar and the slot in the link to pivotally secure the walker bar to the link. The slots and pins of the front links 59 are similar to the slot 64 and pin 65 of the front links 63, and the pivot pins normally rest in the bottom ends of the corresponding slots.

Each of the walker bars 17 comprises a member of channel-shaped cross-section having a pair of spaced-apart, substantially parallel side-walls 66 and a bottom wall 67. The side-walls 66 are provided along their upper edges with respective series of contiguous, rearwardly-directed serrations 68, and the bottom wall 67 is provided in its upper surface with a series of contiguous, rearwardly-inclined notches 69. The bottom wall 67 may be formed of thick material and have downward extensions 70 where the rear links 58 and 59 are connected thereto, these extensions being recessed, as indicated at 71, to provide for pivotal movement of the links relative to the walker bars. A similar construction may be pro-

vided for the attachment of the front links 59 and 53 to the corresponding straw-walker bars.

A respective cable sheave 74 is mounted on the upper end of each forward bracket 57 and 62, and a respective cable 75 passes under each sheave 74 and has one end connected to the pivot pin of the corresponding walker bar 17. A respective coiled tension spring 19 is secured at one end to the opposite end of the cable, and such spring has its end opposite the cable connected to the associated rear link 58 or 61 to resiliently urge the forward end of the walker bar downwardly with the pins 65 at the bottoms of the corresponding slots 64.

With this arrangement, when the front end of one of the pick-up fingers 18 strikes an obstruction or a sudden rise in the ground, it may rise, lifting the front end of the corresponding walker bar, and pulling the corresponding cable 75 around the sheave 74, at the same time stretching the spring 19. After the obstruction or rise in the ground is passed, the spring returns the front end of the walker bar to its normal position. The pick-up finger and walker-bar assemblies may move rearwardly against the tension of the corresponding springs 16, as well as upwardly, to avoid any shock to the mechanism. As the spring returns the walker-bar-and-finger assembly from a lifted and rearwardly-disposed position to its normal operative position, the corresponding rear link 58 or 61 contacts the rear edge of the link-receiving recess 71 in the walker bar, and this provides a positive stop for forward movement of the walker-bar-and-pick-up finger assembly.

Each of the pick-up fingers 18 comprises a body of channel-shaped cross-section having a pair of substantially parallel, spaced-apart side-walls 80, each provided along its upper edge with a series of contiguous, rearwardly-directed serrations 81, and a bottom wall 82 extending between the two side-walls at the lower edges of the latter. The bottom wall 82 has in its upper surface a series of contiguous, rearwardly-directed notches 83 for lifting small pieces of material and loose seed onto the associated walker bar 17.

The two side-walls 80 are provided at corresponding ends with arcuately-curved end portions 84 provided substantially at their centers of curvature with apertures receiving a pivot pin 85 which also extends through aligned apertures in the corresponding, adjacent ends of the side-walls 66 of the walker bar 17, to pivotally connect the pick-up finger 18 at its rearward or proximal end to the forward end of the straw-walker bar. A coiled torsion spring 86 surrounds the pin 85 between the side-walls of the walker bar and has a loop 87 bearing against the bottom wall of the pick-up finger, and ends 88 bearing against the bottom wall of the walker bar to resiliently urge the pick-up finger to its normal position in which it constitutes a substantially uninterrupted continuation of the walker bar. Relative spring-induced movement between the pick-up finger and the walker bar is limited by contact of the adjacent ends of the bottom walls 67 and 82 of the walker bar and the pick-up finger, which bottom-wall ends constitute shoulders cooperating to limit relative movement of the pick-up finger and walker bar in the corresponding direction. At the distal end of the pick-up finger the side-walls 80 have their ends so inclined to the direction of the bottom wall 82 that these ends are substantially parallel to the surface of the ground upon which the windrow

pick-up machine is supported, and the bottom wall is provided at its lower end with a curved, rearwardly-directed extension 89 aligned with the adjacent ends of the side-walls 80 to provide a ground-bearing foot which is substantially parallel to the surface of the ground and supports the pick-up finger against digging into the ground.

10 A generally triangular gusset plate 90 is inserted in a slot provided in the curved, lower end portion of the bottom wall 82 substantially mid-way between the side-walls 80, and is disposed substantially parallel to the side walls. This plate 90 not only reinforces the foot 89 of the pick-up finger, but extends somewhat forwardly of this foot to assist in picking up small pieces of material from the ground.

15 The operation of the pivotally-mounted pick-up finger is diagrammatically illustrated in Figure 4 where the finger is shown in contact at its lower end with an obstruction, such as a stone. As the corresponding walker bar is moved forwardly and upwardly after the pick-up finger has been brought into contact with the ground, 20 the corresponding pin 65 will be at the bottom of the slot 64 in the respective front link 63, and there is relatively little "give" or resiliency to the walker bar under these conditions, the slot 64 being provided to provide a limited amount 25 of resiliency to limit motion between the walker bars and the cranks 13 and 14, so that the cranks may continue to rotate, even though the walker bars are stopped short of their full downward movement by contact of the pick-up 30 fingers with the ground. The bottom end of the pick-up finger is brought into engagement with an obstruction, as illustrated in Figure 4, upon forward and upward movement of the walker bar, and under these conditions the front end 35 of the pick-up finger will move downwardly and rearwardly relative to the front-end portion of the walker bar against the force of spring 86, so that the pick-up finger may be carried upwardly until it clears the obstruction. As soon as the 40 bottom end of the pick-up finger has cleared the obstruction, the spring 86 will immediately return the pick-up finger to its normal, operative position relative to the corresponding straw-walker bar.

45 50 This provides a necessary "give" or resiliency in the walker-bar and pick-up finger assemblies under conditions which might otherwise break or seriously damage the walker bars.

55 It will be noted that the walker bars are curved somewhat downwardly near their forward ends, which shape of the walker bars positions the associated pick-up fingers so as to materially facilitate the disengagement of the fingers from a ground-carried obstruction, as the fingers are 60 moved relative to the walker bars against the force of spring 86.

65 The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

70 75 What is claimed is:

1. A straw-walker bar and pick-up finger assembly for a windrow pick-up machine compris-

ing a bar of channel-shaped cross-section having spaced-apart, substantially parallel side-walls each provided in its upper edge with a series of rearwardly-directed, contiguous serrations, and a bottom wall provided in its upper surface with a series of rearwardly-directed, contiguous notches, a pick-up finger of channel-shaped cross-section having spaced-apart, substantially parallel side-walls each provided in its upper edge with a series of rearwardly-directed, contiguous serrations and each pivotally connected at one end to the adjacent end of a corresponding side-wall of said bar, and a bottom wall provided in its upper surface with a series of rearwardly-directed, contiguous notches, and a spring connected between said bar and said pick-up finger urging said finger forwardly and upwardly relative to said bar.

2. A straw-walker bar and pick-up finger assembly for a windrow pick-up machine comprising a bar of channel-shaped cross-section having spaced-apart, substantially parallel side-walls each provided in its upper edge with a series of rearwardly-directed, contiguous serrations, and a bottom wall provided in its upper surface with a series of rearwardly-directed, contiguous notches, a pick-up finger of channel-shaped cross-section having spaced-apart, substantially parallel side-walls each provided in its upper edge with a series of rearwardly-directed, contiguous serrations and each pivotally connected at one end to the adjacent end of a corresponding side-wall of said bar, and a bottom wall provided in its upper surface with a series of rearwardly-directed, contiguous notches, and a spring connected between said bar and said pick-up finger urging said finger forwardly and upwardly relative to said bar, said bar and said finger having cooperating shoulders thereon limiting spring-induced movement of said finger relative to said bar.

3. A straw-walker bar and pick-up finger assembly for a windrow pick-up machine comprising a bar of channel-shaped cross-section having spaced-apart, substantially parallel side-walls each provided in its upper edge with a series of rearwardly-directed, contiguous serrations, and a bottom wall provided in its upper surface with a series of rearwardly-directed, contiguous notches, a pick-up finger of channel-shaped cross-section having spaced-apart, substantially parallel side-walls each provided in its upper edge with a series of rearwardly-directed, contiguous serrations and each pivotally connected at one end to the adjacent end of a corresponding side-wall of said bar, and a bottom wall provided in its upper surface with a series of rearwardly-directed, contiguous notches, and a spring connected between said bar and said pick-up finger urging said finger forwardly and upwardly relative to said bar, adjacent ends of the bottom walls of said finger and said bar constituting shoulders limiting spring-induced movement of said finger relative to said bar to a relative position in which said finger constitutes an operative continuation of said bar.

4. A straw-walker bar and pick-up finger assembly for a windrow pick-up machine comprising a bar of channel-shaped cross-section having spaced-apart, substantially parallel side-walls each provided in its upper edge with a series of

rearwardly-directed, contiguous serrations, and a bottom wall provided in its upper surface with a series of rearwardly-directed, contiguous notches, a pick-up finger of channel-shaped cross-section having spaced-apart, substantially parallel side-walls each provided in its upper edge with a series of rearwardly-directed, contiguous serrations and each pivotally connected at one end to the adjacent end of a corresponding side-wall of said bar, and a bottom wall provided in its upper surface with a series of rearwardly-directed, contiguous notches, and a spring connected between said bar and said pick-up finger urging said finger forwardly and upwardly relative to said bar, said finger having the ends of its side-walls at its distal end inclined in accordance with the inclination of said bar when operatively mounted in a windrow pick-up machine so that said side-wall ends are substantially parallel to the ground, and having at its distal end a rearwardly-directed bottom-wall extension substantially in alignment with the ends of said side-walls.

5. A straw-walker bar and pick-up finger assembly for a windrow pick-up machine comprising an elongated walker bar of channel-shaped cross-section mountable in a forwardly and downwardly-inclined position on a windrow pick-up machine, a pick-up finger of channel-shaped cross-section pivotally secured at one end to the forward end of said bar, and a spring connected between said bar and said finger resiliently urging said finger to a position relative to said bar in which said finger constitutes an uninterrupted continuation of said bar, the distal end of said finger being movable downwardly and rearwardly relative to said bar upon contact of the distal end of said finger with an obstruction.

6. A straw-walker bar and pick-up finger assembly for a windrow pick-up machine comprising an elongated walker bar of channel-shaped cross-section mountable in a forwardly and downwardly-inclined position on a windrow pick-up machine, a pick-up finger of channel-shaped cross-section pivotally secured at one end to the forward end of said bar, and a spring connected between said bar and said finger resiliently urging said finger to a position relative to said bar in which said finger constitutes an uninterrupted continuation of said bar, the distal end of said finger being movable downwardly and rearwardly relative to said bar upon contact of the distal end of said finger with an obstruction, said finger having a ground-engaging foot on the distal end thereof to support said finger against digging into the ground.
